UNITED STATES PATENT OFFICE

HARRY HUGHES HARRISON, OF LIVERPOOL, AND SIDNEY REYNELL SMITH, OF LONDON, ENGLAND, ASSIGNORS TO AUTOMATIC TELEPHONE MANUFACTURING COMPANY LIMITED, OF LIVERPOOL, ENGLAND

ROTARY DISTRIBUTOR FOR USE IN TELEGRAPH OR LIKE SYSTEMS

Application filed December 31, 1925, Serial No. 78,577, and in Great Britain January 14, 1925.

The present invention relates to rotary distributors of the kind used in telegraph systems; such distributors are usually employed in connection with synchronous telegraph systems for connecting up particular circuits at the transmitting and receiving ends of the line at the same instant, or allowing for orientation, at an instant at which the signals sent to the line by a transmitter can be received correctly by the corresponding receiving apparatus.

In known distributors of this type, it has been usual for the rotating brushes to wipe over contacting segments mounted in an insulating disc, the disc and segments being adjustable relatively to their supporting frame to allow for orientation. The brushes themselves usually consist of a bunch of metallic threads or wires, and brushes of this type from their nature require frequent attention and adjustment, as in view of the importance of the phase relationship between the distributors at the transmitting and receiving ends, any stray ends of the brush wires would completely upset the functioning of the apparatus.

The object of the present invention is to provide an improved and simplified type of distributor requiring considerably less attention for maintenance purposes and of a construction which is simple and cheap.

The principal characteristic of the new type of distributor is that it is designed on the lines of a step-by-step switch having motion in a single plane as used in automatic telephone systems for a subscriber's line switch, and accordingly while broadly the invention consists in modifying such a line switch for use as a rotary distributor in telegraph systems, it possesses a number of novel features. The features which contribute towards giving rotary distributors according to the invention advantages over distributors of the old type are in the following paragraphs individually set out.

According to one feature of the invention, the brushes consist of single metallic members stamped out of thin sheet metal, for instance phosphor-bronze, the brushes being shaped and bent so as to present a trailing

end which tends to press against or between the stationary contacts, according to its position. This type of brush is bound to give contact at a very precise instant, thus permitting accurate adjustment and will run continuously for long periods without requiring any attention owing to loss of adjustment. 55

According to another feature of the invention the brushes are adapted to engage the stationary contacts on both sides simultaneously. Preferably for this purpose each brush consists of two members of similar shape but having their ends bent in opposite directions so as to press on either side of the 60 contacts. 65

A further feature of the invention which is closely connected with that just mentioned, is that the fixed contacts project from insulating supports in a radial direction; consequently when the brushes are not engaging with the fixed contacts, they will engage with each other, there being no solid insulation provided between the adjacent fixed contacts in the track of the brushes. 70 75

Still another feature of the invention is that the stationary contacts are secured in a frame supported directly by the shaft and adapted to be moved bodily relatively to the shaft and to the main support; this construction permits orientation to be carried out in a very simple manner. 80

These features and others of less importance will be better appreciated from the following description taken in conjunction with the accompanying drawings of a preferred form of the invention, which is given by way of example. It will be understood however that the invention is not limited to the precise construction shown and that various detail modifications could be made without exceeding its scope. 85 90

Referring now to the drawings, Fig. 1 may be considered as an elevation of the improved distributor as mounted in position and Fig. 2 will then be an inverted plan of the device unmounted. Fig. 1 it should be mentioned, is a section of Fig. 2 along the line 1-1. In Fig. 1 the main frame on which the distributor is mounted is indicated by 100

1 and it is supported at one end by plate 2 which is fixed to the main frame by the screws 3, 3. The fixed contacts 4 comprise sheet metal stampings, for instance of phosphor-bronze, of appropriate shape and having the correct circumferential length. These contacts are mounted between insulating plates 5, separated by spacing plates 6, the whole being held together by the bolts 7. It will be understood of course that the contacts are cut away as indicated by the dotted line so that no electrical connection is made with the holding bolts. The lowermost spacing plate has right angled extensions 7' by means of which connection is made to the side frame 8 by the screws 9. The side frame, which is of the special shape shown, carries bearings 10 and 11, through which passes the shaft 12, which has one bearing on the plate 2. At the other end of the shaft is a coupling 13, by means of which connection is made to a driving motor, from which also support is obtained for the other end of the shaft. It will be apparent that the contact assembly is free to rotate relatively to the frame 1 and to the shaft 12 and this movement is limited and defined by the screw 14. This screw is threaded in a pillar 15 secured to the frame 1 and having a recess in which is housed a spring 16, which tends to turn the contact assembly away from the pillar. Orientation may therefore be effected accurately by operating the screw 14, the spring 16 keeping the plate 7' pressed up against the head of the screw. For a reason which will be more fully considered subsequently orientation should only be effected with the switch shown while the brushes are rotating.

40 The brushes 17 are conveniently of the shape shown in order to provide flexibility and preferably two separate members co-operate so as to engage a fixed contact on both sides simultaneously. The various brushes are separated by insulating washers and are held together by the nut 18 so as to form a solid unit. This unit is rigidly fixed to the shaft 12 by the set screw 19 so as to rotate with the shaft.

50 In the arrangement shown there are two rows of fixed contacts with their corresponding brushes, but it will be appreciated that it is a simple matter to add other rows if they should be required. With this construction of distributor, the different rows of contacts are all located at the same radius instead of being located at different radii as has been usual with distributors of the flat disc type used hitherto. It will be noted that with the arrangement illustrated the brushes are double ended, while the fixed contacts occupy approximately a semi-circle. This arrangement is advantageous in giving free access to the distributor and simplifying its construction and assembly, but it will be un-

derstood that a full circle could also be used, or the contact assembly could occupy one-third or other fraction of the full circle.

Electrical connections are made to the rotating brushes by the feed brushes 20 which are split and have their ends turned in opposite directions so as to engage with each of the pair of brushes wiping over a particular contact row. Engagement is effected at an enlarged portion near the shaft so that contact can be maintained whatever the position of the moving brushes. It will be clear that when the latter encounter the outer end of the feed brush they will pass over it as over an ordinary fixed contact.

In the form of distributor shown, the ends of a co-operating pair of brushes meet in a V, as may be seen from Fig. 2. Consequently in order to avoid damage to the brushes or contacts, it is desirable that orientation shall be effected while the brushes are moving so as to avoid any possibility of the fixed contacts being moved forward relatively to the brushes. This limitation could obviously be overcome by extending the brushes backwards and arranging for the tips to diverge, but this entails a somewhat more complicated manufacturing process and should not in general be necessary.

What we claim as new and desire to secure by Letters Patent is:—

1. A rotary distributor for use in telegraph or like systems comprising in combination a fixed supporting frame, a rotatable shaft carried by said frame and adapted to be continuously driven, contact supports of arcuate form carried by said shaft, metallic contact members of selected circumferential length arranged to be held by and to project in a radial direction from said supports, and metallic brushes secured to said shaft and arranged to engage with said contact members successively when said shaft is rotated.

2. A rotary distributor for use in telegraph or like systems comprising in combination a fixed supporting frame, a rotatable shaft carried by said frame, contact supports carried by said shaft, metallic contact members located in a single plane and arranged to project in a radial direction from said supports, a pair of L-shaped brushes secured to said shaft and located on either side of the plane of said contact members and radial trailing edges on said brushes inwardly bent so as to engage said contact members in turn on both sides simultaneously on a radial line when said shaft is rotated.

3. A rotary distributor for use in telegraph or like systems comprising in combination a fixed supporting frame, a plurality of metallic contact members, supports for said contact members, a rotatable shaft, bearings for said shaft on said supporting frame, bearings for said supports on said shaft, metallic brushes secured to said shaft and ad-

justing means for altering the position of said supports relatively to said supporting frame.

4. A rotary distributor for use in telegraph or like systems comprising in combination a fixed supporting frame, a plurality of metallic contact members, supports for said contact members, a rotatable shaft, bearings for said shaft on said supporting frame, bearings for said supports on said shaft, metallic brushes secured to said shaft, a threaded pillar carried by said supporting frame, a screw adapted to engage in said pillar and a spring for holding said supports against the head of said screw so that the position of said supports relatively to said supporting frame may be altered by operating said screw.

In testimony whereof we affix our signatures.
